SPACE HEATER

Stanley F. Jackes, University City, Mo., assignor to Jackes-Evans Manufacturing Company, St. Louis, Mo., a corporation of Missouri

Application April 16, 1956, Serial No. 41,084

Term of patent 14 years

(Cl. D81—10)

FIG.1.

FIG.3.

FIG.2.

Fig. 1 is a perspective view of a space heater embodying my new design,

Fig. 2 is an elevational view showing the side of the space heater opposite to that shown in Fig. 1, a gas burner fixture and shut-off valve being shown in broken lines for purposes of illustration, and

Fig. 3 is a top plan view of the space heater.

I claim:

The ornamental design for a space heater, substantially as shown and described.
